UNITED STATES PATENT OFFICE.

HARRY C. GOODRICH, OF CHICAGO, ILLINOIS.

RUFFLING ATTACHMENT FOR SEWING-MACHINES.

SPECIFICATION forming part of Letters Patent No. 333,515, dated January 5, 1886.

Application filed January 2, 1885. Serial No. 151,885. (No model.)

To all whom it may concern:

Be it known that I, HARRY C. GOODRICH, residing at Chicago, in the county of Cook and State of Illinois, and a citizen of the United States, have invented a new and useful Improvement in Ruffling Attachments for Sewing-Machines, of which the following is a full description, reference being had to the accompanying drawings, in which—

10 Figure 1 is a side elevation of the complete attachment; Fig. 2, a bottom view of the presser-foot and the compensating head or block; Fig. 3, an enlarged detail, being a longitudinal section through the presser-foot and block or head; Fig. 4, a detail showing a presser-foot and a modification in the manner of attaching the head or block; Fig. 5, a bottom view of the parts shown in Fig. 4; Fig. 6, a longitudinal section enlarged of the parts 20 shown in Fig. 4. Fig. 7 shows a head or block with a serrated biting-edge.

The inequalities of fit between the co-acting faces of a presser-foot and the feed of the machine in connection with a ruffling blade or attachment renders the operation of the present construction of ruffling attachments more or less imperfect, for the reason that the material operated upon is not pressed with equal force the entire width where it passes beneath the presser-foot, owing to the fact that one side of the foot acts while the other side does not, leaving a space in which the material can slip either by the advance of the ruffling-blade or the withdrawal thereof, pushing a crimp through without forming it, or withdrawing the crimp after it has been formed, thus producing an unequal crimp or ruffle.

The object of this invention is to overcome this objection in the present style of ruffling attachments; and its nature consists in providing a rocking and spring head or block located on the under side of the presser-foot and acting independent of the foot, to adapt itself to the plane in which the acting face of the feed of the machine stands, irrespective of the plane of the under face of the presser-foot, in combination with a reciprocating ruffling-blade, as more fully hereinafter described.

In the drawings, A represents a presser-foot 50 having, as shown, formed therewith a socket portion, A', for attachment to the presser-bar

of a sewing-machine, in which socket, at the rear face thereof, is a recess, a', to receive an arm carrying a separator-plate, (not shown,) and the presser-foot proper, A, is provided with a needle-hole, a, as usual, for the passage of the needle, and, as shown, the presser-foot at its forward or toe end has an upward-extending arm, A", for carrying the ruffling-blade and its operating devices, which arm, in one of its side faces, has grooves a" for guiding overlay-strips when used.

B is the head or block, which, as shown in Figs. 1, 2, and 3, has its forward edge beveled off and its under face at the forward end undercut, so as to form a depression, b, with a biting-edge, b'; but the undercut portion b might be omitted, and the under face of the head or block left with an even surface. This head or block B, as shown, is attached to a plate, B', having a spring action, which plate at its rear end has a turned-up portion, B", which enters a slot, b", extending up vertically into the presser-foot, and the upturned end is pivotally secured in such slot by a pin, b³, 75 which pin passes into a hole in the heel end of the presser-foot, its forward end passing through a hole in the part B" and entering a hole in the presser-foot forward of the end B", as shown in Fig. 3, thus supporting the head 80 or block, so that it can rock endwise, to allow one end to rise or fall, as may be desired, for the block to fit the plane of the feed. The head or block B is brazed or otherwise securely fastened to the spring or spring-plate 85 B', and the upturned end B" is shorter than the depth of slot b", into which it enters to allow of the rocking movement of the spring or spring-plate from the pin or pivot b³. The head or plate B has a downward pressure 90 through the spring or spring-plate B', the amount of which is regulated by a screw, b⁵, passing through the presser-foot, and its end engaging the spring or spring-plate, and this spring or spring-plate B' also allows the head 95 or block to rise and adapt itself to different thicknesses of material.

C is the ruffling-blade, the forward end of which is serrated or provided with teeth, as usual, and is also provided with a slot which 100 coincides when the parts are together with the needle-hole a, and the block or head B

has a semicircular recess coinciding with the needle-hole a , the biting-edge b' , when the parts are in position for use, lying in a center line with the needle-hole a , so as to be in line, 5 or nearly so, with a vertical plane through the center of the needle. The ruffling-blade at its rear end is attached to an arm, C' , by rivets or in any other firm manner, and, as shown, a guide-plate, c , is also attached to the arm C' c by a socket, c' , to leave a space, c'' , between it and the under face of the arm, for the passage of the strip to be beveled.

D is an arm, the lower end of which is turned at right angles to form the arm C' , and 5 the upper end of which has a side head, D' , carrying set-screws d d' , by means of which the arm D is gaged to swing back and forth, as required for the amount of throw to be given to the ruffling-blade.

o E is a lever having a slot, E' , for adjustment to the needle-bar of the machine, and having at its pivoted end ears, one of which, e , only is shown, by means of which the pendant or arm D is operated.

25 An adjusting-plate is in practice to be provided, having on one side an ear, f , to be engaged by the head or projection e , and to engage with the end of the set-screw d , to carry the ruffling-blade back, the forward throw of 30 the ruffling-blade being accomplished by the engagement of the projection or head of the lever E , opposite to the head e , with the end of the set-screw d' .

The parts represented by the letters C , C' , D , 35 D' , E , E' , c , c' , c'' , d , d' , e , and f may be of the form of construction and arrangement shown, or any of the usual and well-known forms of construction and arrangement, and, as shown, the lever E and pendant or arm D are supported from the same pin or pivot f' , projecting out from the upper end of the arm A' .

As shown in Figs. 4, 5, and 6, the head or block B is formed with the spring or spring-plate B' , but the head or block shown in Figs. 45 1, 2, and 3 could be applied to the construction shown in Figs. 4, 5, and 6, by brazing or otherwise securing the head or block to the spring or spring-plate.

As shown in Figs. 4, 5, and 6, the spring or 50 spring-plate is extended back sufficiently far to have the upturned end B'' come outside of the rear or heel end of the presser-foot, where it is secured in a pivotal manner by a screw or pin, b^3 , entering the rear or heel end, and, 55 as shown, the pressure-adjusting screw b^5 , instead of passing nearly vertically through, as shown in Fig. 3, is inclined somewhat, but its action is precisely the same as that of the screw shown in Fig. 3, and, as shown, the forward end of the head or plate B has its biting-edge b' formed by turning the end of the plate so as to have a V shape, and when so formed a space, b , is left for the crimps or ruffles to clear themselves after passing the biting-edge, 60 and the under face of the presser-foot, at the point where the end of the head or block is

located, has a recess, A^3 , into which the end of the block can pass, to allow of vertical play of the head or block B for different thicknesses of material.

The screw b^5 forms a fulcrum or bearing-point to steady the block or plate in its endwise movement, as well as a means for adjusting the pressure; but the head or plate B , with its spring or spring-plate B' , could be used 75 without the pressure-adjusting screw, so far as the production of an endwise tip is concerned, to adjust the bearing-face to correspond with the plane of the feed; and to facilitate the rocking of the head or plate for this 80 purpose, the bearing-point might be cast or formed on the under surface of the presser-foot.

In use the device is attached to the presser-bar of a sewing-machine and the material is 85 placed in position in the usual manner, with the piece on which the ruffle is to be sewed between the separator and the feed, and the strip to be ruffled between the separator and ruffling-blade and over the piece on which it 90 is to be sewed, and with the piping, band, or overlay in the grooves a'' , the whole to pass beneath the presser-foot. The advance of the ruffling-blade carries forward the crimp, forcing it beneath the biting-edge b' of the block 95 or plate, to be there caught and firmly held, and as the head or plate is free to adapt itself to the plane of the feed the crimp forced under will be held for the entire width of the head or plate with a uniform and equal pressure, by which one side cannot slip, and the crimp forced under will be held, forming a 100 backing for the next succeeding crimp, thereby insuring the formation of such next crimp, and the first crimp formed, as the the next one 105 is forced under the biting-edge, will be forced out, passing beneath the head or plate and entering the recess formed by the cut-away portion b , which portion leaves a sufficient space for the crimp formed and caught by the thread 110 to pass freely from beneath the biting-edge as the next crimp is forced under such edge. The spring action of the head or plate insures a firm pressure on the material the full width 115 of the head, and at the same time leaves the head perfectly free to rise and adapt itself to different thicknesses of material, and any degree of pressure desired can be produced by forcing the spring or spring-plate down through the adjusting-screw b^5 .

The compensating head or plate can be 120 readily applied to ruffling attachments of any of the usual constructions, all that is required being to pivot the spring or spring-arm to the presser-foot and provide a projection on which the head or plate can rock, either by means of an adjusting-screw passing through the foot or a projection formed on the under face of the foot, and when applied a uniform series of crimps will be produced, as the crimps 130 formed are forced under and held by the biting-edge until caught by the thread, and the

pressure of the head or block will extend its full width, so that the crimp cannot slip on one side while being held on the other.

The head or block shown in Fig. 7 with the 5 series of serrations on its forward edge produces a firmer hold on the material passing beneath the head or block, as the contact-surface is rough to an extent sufficient to prevent easy slipping, and this form of head or 10 plate can be used with material having a very smooth finish.

I do not herein broadly claim the combination 15 with, as such constitutes the subject-matter of my application filed May 19, 1885, Serial No. 166,021; nor do I broadly herein claim in a sewing-machine ruffler having a reciprocating ruffling-blade, a foot part 20 recess in its sole, and provided with a supplemental presser-foot or sole-piece within said recess, and with a spring or springs adapting the latter to press independently upon the crimps or gathers as they are successively 25 completed and left beneath it, as such is embraced in my application filed December 29, 1884, Serial No. 151,882; nor do I herein broadly claim in a sewing-machine ruffler having a reciprocating ruffling-blade a foot part 30 constructed with a pressing-surface which rests upon the sewed ruffles or gathers behind that point at which the crimps or gathers are successively completed or finished, and provided at the point last named with a supplementary 35 presser part or sole-piece free to rise and fall independently of the pressing-surface, as such is embraced in my aforesaid application, No. 151,882; nor do I claim herein the combination, with a recessed presser-foot and a ruffling- 40 blade, of a compensating block or plate, arranged at the under side of the presser-foot, and a torsion-spring carrying the block and permitting it to rise and fall and twist itself, as required, for bearing purposes, as such is 45 embraced in my aforesaid application, No.

151,882; nor do I here claim the combination of a non-rocking presser-foot having a recess on its under side, and a block rocking endwise on a bearing-point and located in the recess, with a reciprocating ruffling-blade, as such is 50 embraced in my application filed December 29, 1884, Serial No. 151,881; and, finally, I do not herein claim in a sewing-machine ruffler having a reciprocating ruffling-blade a foot part constructed with a pressing-surface which 55 rests upon the sewed ruffle or gather behind the point at which the crimps or gathers are successively completed or finished, and provided with a supplemental presser part or sole-piece which rests upon the crimps or gathers at said point, where they are completed or finished, and with an independent presser spring or springs between the latter and the top of said foot part, as such is embraced in my application filed December 29, 1884, Serial No. 151,884. 60

What I claim as new, and desire to secure by Letters Patent, is—

1. The combination, with a presser-foot and a reciprocating ruffling-blade, of a spring pivotally connected with the presser-foot and a head or plate, B, connected with said spring, substantially as and for the purpose described. 70

2. A presser-foot, A, having a bearing point on its under side, in combination with a head 75 or plate, B, spring B', pivotally attached to the foot, and a reciprocating ruffling-blade, substantially as and for the purpose specified.

3. A presser-foot, A, and adjusting-screw b⁵, in combination with a ruffling-blade, C, a 80 head or plate, B, and spring or spring-plate B', pivotally attached to the presser-foot, for increasing the bearing-pressure on the head or plate without interfering with the rocking movement thereof, substantially as and for the 85 purpose specified.

HARRY C. GOODRICH.
